UNITED STATES PATENT OFFICE.

EMIL ERICKSSON, OF CHICAGO, ILLINOIS, ASSIGNOR TO WM. A. FIELD COMPANY,
OF CHICAGO, ILLINOIS, A CORPORATION OF ILLINOIS.

MEANS FOR CORRECTING PRINTING PLATES.

Application filed November 8, 1923. Serial No. 673,473.

To all whom it may concern:

Be it known that I, EMIL ERICKSSON, a citizen of the United States, residing at Chicago, in the county of Cook and State of Illinois, have invented certain new and useful Improvements in Means for Correcting Printing Plates, of which the following is a specification.

In preparing printing plates for the press, 10 it is necessary to true up or level the printing surface by the application of pressure to a degree necessary to transfer any variations in level from the type surface to the back of the plate, which latter may be afterwards shaved or otherwise treated to remove such inequalities due to variations in thickness and other causes.

In modern practice, it is customary to true up the printing plates in specially prepared presses, and the present invention relates to a backing for the plates to be corrected, and so constructed as to yield locally to the degree required to impart the pressures necessary to bring the printing surface of the plate to a true plane or other intended configuration. It will be understood from the above that the invention has application to the correction of curved plates for cylindrical presses as well as those intended for use on flat presses.

In performing the service indicated, it has usually been the practice to provide backing sheets of paper or composition provided with an embossed surface adapted to be locally crushed down in the correction process, which practice used up the sheet and rendered it unfit for further use, but the present invention is directed to a permanent backing intended to constitute an integral portion of the press as a whole and so constructed as to be capable of continuous use throughout a long period of time.

In the drawings:

Figure 1 is a sectional elevation showing the upper and lower plates of a press with the correction members of the present invention bearing against a printing plate in its uncorrected state;

Fig. 2 is a similar view showing the relation of the same parts after corrections;

Fig. 3 is a perspective detail largely in section showing the correction members of the present invention; and

Fig. 4 is a sectional detail showing a modified form of the same.

The upper plate of the correction press 10 is provided with apertures 11 through which are extended gas burners 12 for heating the press plate to the degree required to render pliable the printing plate 13 which is being corrected. The printing plate is provided with a type surface 14 which, it will be noted from inspection of Fig. 1, is more or less irregular prior to the correcting process.

The upper press plate cooperates with a lower press plate 15 upon which is mounted a relatively thick backing layer 16 of rubber or other yielding material. Above the rubber backing is located a metal face plate 17 provided with a large number of apertures 18, each of which receives a pin 19 provided on its lower end with a head 20 which bears against the rubber backing. The pins are of a length to bring their upper or contact ends normally slightly above the surface of the face plate 17 and into contact with the back surface of the printing plate under correction.

In Fig. 4 is shown a slight modification in lieu of a rubber backing, a metal plate 21 is employed provided with perforations 22 adapted to receive and guide the lower ends 23 of pins 24 provided with flanges 25, which latter furnish heads for the contact of coil springs 26 which serve to hold the pins in elevated position. In this construction the face plate 17 is held in spaced relation to the backing plate 21 by means of tie rods 27 and spacers 28, the tie rods also serving to bolt the correction elements to the lower press plate 15, or other plate laid thereon.

In using the correction members of Figs. 1 and 2, the printing plate is inserted in position, as in Fig. 2, and heated by contact with the heated surface of the upper press plate. Thereafter pressure is applied which has the effect of bending the plate and transferring the inequalities from the face

of the plate to the back thereof, as in Fig. 2. During this operation, the pins will be depressed in varying degree against the yielding surface of the rubber backing, so that inequalities and imperfections in the printing surface will be eliminated. By providing a plurality of pins furnishing contact points adapted to yield locally to the required amount, every portion of the printing plate will have the required pressure imparted thereto to insure the necessary correction.

The correction elements of Fig. 4 are employed in the same manner as that above described, but in this case, the individual springs subserve the same function as the rubber backing sheet and locally yield to the required amount in each instance to secure the necessary correction.

20 By employing spaced contact pins in conjunction with a rubber backing, displacement areas are provided between the heads of the pins for permitting a displacement or bulging up of the rubber to the degree required to 25 compensate for the depression of the rubber at points in contact with the pin heads. This renders the arrangement far superior to one in which a rubber sheet is alone employed for contact with the plate being corrected for the reason that without the pins, the rubber, in unbroken contact with the printing plate and subjected to a varying pressure due to inequality in the plate surface, will have difficulty in accommodating 35 itself locally to the distortional influence of the pressure applied, so that excessive pressures may be required, which may tend to distort or impair the type surface or render the application of an excessively high 40 temperature necessary in order to effect correction. By providing a multiplicity of point contacts, the displacement areas are subdivided, so that small areas of the rubber between the pin heads can readily distort 45 to locally accommodate all variations in pressure which may be encountered. At the same time the interposed pins serve to protect the rubber from the deleterious effects of the heat applied to the printing plate, and 50 permit the use of such temperatures as may be best fitted to render the plate pliable without directly imparting such heat to the rubber.

For the reasons outlined, the use of the 55 present invention permits of a much greater variation in heat and pressure than might otherwise be practically employed and permits the correction elements to be continuously used without material wear or impairment.

I claim:

1. In devices for correcting printing plates, the combination of a yieldable backing, a rigid face plate, and yieldable contact 65 members carried by the face plate and bear-

ing against the yieldable backing, substantially as described.

2. In devices for correcting printing plates, the combination of a rigid face plate, and contact elements yieldably carried by 70 the face plate, substantially as described.

3. In devices for correcting printing plates, the combination of a rigid face plate, a plurality of contact elements carried by 75 the face plate, and yieldable backing means for the contact elements, substantially as described.

4. In devices for correcting printing plates, the combination of a rigid face plate, 80 a plurality of closely spaced correction elements slidably mounted through the face plate and normally projecting above the face plate, and yieldable backing means for the contact elements, substantially as described.

5. In devices for correcting printing plates, the combination of a rigid face plate provided with a plurality of apertures, pins inserted through the apertures and normally projecting above the face plate, and 90 yieldable backing means for said pins, substantially as described.

6. In devices for correcting printing plates, the combination of a rigid face plate provided with a plurality of apertures, pins inserted through the apertures and normally projecting above the face plate, and a backing layer of yieldable material bearing 95 against said pins, substantially as described.

7. In devices for correcting printing plates, the combination of a face plate provided with closely spaced apertures, pins inserted through said apertures and projecting above the face plate, and yieldable means bearing against the opposite ends of 100 said pins, substantially as described.

8. In devices for correcting printing plates, the combination of a face plate provided with closely spaced apertures, pins inserted through said apertures and projecting above the face plate, and a backing layer of yieldable material bearing against the opposite ends of 105 said pins, substantially as described.

9. In devices for correcting printing plates, the combination of a face plate provided with closely spaced apertures, pins projecting through said apertures and beyond the acting surface of the face plate, 110 heads on the opposite ends of said pins, and yielding means bearing against said heads for normally holding the pins projected, substantially as described.

10. In devices for correcting printing plates, the combination of a face plate provided with closely spaced apertures, pins slidably mounted through said apertures and normally projecting above the face plate, said pins being provided with heads, 115 and a backing layer of yieldable material 120

bearing against said heads and adapted to yield locally to variations in pressure, substantially as described.

11. In devices for correcting printing plates, the combination of a relatively thick and rigid face plate provided with apertures, a plurality of pins projecting through said apertures and normally extending be-

yond said face plate and provided with heads on their rear ends, and a relatively thick backing layer of rubber bearing against said heads and held in spaced relation to the face plate by said heads, substantially as described. 10

EMIL ERICKSSON.
